(57) CLAIM

The ornamental design for a hanging organizer as shown and described.

DESCRIPTION

FIG. 1 is a front perspective view of the design of the hanging organizer of the present invention;

FIG. 2 is a top plan view of the hanging organizer shown in FIG. 1;

FIG. 3 a front elevation view of the hanging organizer shown in FIG. 1;

FIG. 4 is a left elevation view of the hanging organizer shown in FIG. 1;

FIG. 5 is a rear elevation view of the hanging organizer shown in FIG. 1.

FIG. 6 is a right elevation view of the design of the hanging organizer shown in FIG. 1; and,

FIG. 7 is a bottom plan view of the hanging organizer shown in FIG. 1.

Any broken line depictions illustrate environmental structure and form no part of the claimed design. Any shading and cross-hatching are likewise not features of the design but are used to illustrate surface contours of the illustrated design. The hanging organizer is shown with a symbolic break in its length. The appearance of any portion of the article between the break lines forms no part of the claimed design.
